UNITED STATES PATENT OFFICE

141,659

DESIGN FOR A SCARF

Drusilla G. Carpenter, Dallas, Tex.

Application January 13, 1945, Serial No. 117,413

Term of patent 3½ years

(Cl. D3—16)

To all whom it may concern:

Be it known that I, Drusilla G. Carpenter, a citizen of the United States of America, residing at Dallas, in the county of Dallas and State of Texas, have invented a new, original, and ornamental Design for a Scarf, of which the following is a specification, reference being had to the accompanying drawing, forming part thereof.

Fig. 1 is a perspective view of a scarf, showing my new design, and showing the scarf in its tied position.

Fig. 2 is a view, similar to Fig. 1, taken at an angle of approximately 45° relative to Fig. 1, and

Fig. 3 is a plan view of the scarf in a substantially flat, untied position.

I claim:

The ornamental design for a scarf, as shown.

DRUSILLA G. CARPENTER.
